UNITED STATES PATENT OFFICE.

FRANK SCHILLING, OF MUNCIE, INDIANA.

DESIGN FOR A BOTTLE.

SPECIFICATION forming part of Design No. 31,462, dated August 29, 1899.

Application filed August 7, 1899. Serial No. 726,474. Term of patent 7 years.

To all whom it may concern:

Be it known that I, FRANK SCHILLING, a citizen of the United States, residing at Muncie, in the county of Delaware and State of Indiana, have invented and produced a new and original Design for Bottles, of which the following is a specification, reference being had to the accompanying drawings, forming a part thereof, and wherein like letters of reference indicate corresponding parts in the several views, and in which—

Figure 1 is a perspective view of a bottle, showing my new design; and Fig. 2 is a section on the line 2 2, Fig. 1, looking downward.

As shown in the drawings, the leading or material feature of my design consists of a bottle having the plain side portion A and an ornamented shoulder and neck portion. The ornamentation on the shoulder of the bottle consists of two curved beads A', which intersect each other and extend upwardly and form the points A''. From these points the beads extend downwardly and are curved, as shown at B. At the point of intersection the beads

are broken, leaving a space which is filled 25 with a diamond-shaped projection C. Arranged between the beads are the elliptical-shaped projections D. Between the points A'' are arranged smaller elliptical projections E. Below the beads, where the shoulder commences, is arranged an annular groove F, and between this groove and the beads are arranged elliptical projections H. Around the neck of the bottle is arranged a band I, having a scalloped edge I'. This band is ornamented 30 with a series of elliptical projections K.

Having thus described my invention, what I claim as new, and desire to secure by Letters Patent, is—

The design for a bottle, substantially as 40 shown and described.

In testimony whereof I have hereunto affixed my signature in the presence of two witnesses.

FRANK SCHILLING.
